UNITED STATES PATENT OFFICE.

CECIL B. MAYFIELD, OF WARSAW, ILLINOIS.

HORSE COLLAR.

Application filed October 26, 1923. Serial No. 670,930.

To all whom it may concern:

Be it known that I, CECIL B. MAYFIELD, a citizen of the United States, residing at Warsaw, in the county of Hancock and State 5 of Illinois, have invented certain new and useful Improvements in Horse Collars, of which the following is a specification.

This invention relates to a new and improved horse collar.

10 The principal object of the invention is to provide a horse collar of new and novel construction that is cheap to make, yet strong and durable and which embodies pneumatic cushioning means to increase its efficiency.

15 Further objects of my invention will become apparent during the continuance of the following description.

In the drawings:

Figure 1 is a view in front elevation showing my invention in its preferred embodiment, parts thereof being shown broken away and in section to disclose its interior construction.

20 Figure 2 is a detail view of the ends and of means to fasten the ends.

Figure 3 is a view in cross section taken on line 3—3 of Figure 1.

The main or body portion of the invention which forms the outer casing of the collar 25 is preferably formed of leather or similar material. The collar consists of a cushioned member 10 having overlapping ends 11 and 12 that may be secured together by such means as shown at 13 and 14, and a rim or beaded portion 15 against which the hames bear. In forming the outer casing of the collar, I preferably take a length of material such as shown in Figure 3 and bend it back upon itself to first form the rim 15 and 30 arrange the remaining portions to form the cushion member 10. It will be observed that one edge of the length of material terminates within the cushion member, as at 16, while the other edge is fastened to the rim or beaded portion 15, as at 17. By fastening 35 one edge of the length of material to the rim or beaded portion 15 a compact and durable cushion member is provided.

Within the hollow hame rim or beaded portion 15, I provide a number of lengths, 50 or if preferable, only a single length of heavy hemp rope 18, as shown in Figures 1 and 3. This renders the hame rim substantially rigid and durable.

Immediately within the cushion member 55 10, I provide an inner casing of heavy canvas preferably of spiral construction, as shown at 19. In use, I find it preferable to form the lining 19 of substantially heavy duck tape, wound spirally to relieve pressure 60 on the main casing 10 as will be hereinafter more clearly shown.

A pneumatic tube 20 is positioned within the spiral casing 19 of the cushion member 10, an opening 21 being provided in the 65 cushion member to facilitate the insertion or removal of the tube and to accommodate the valve stem 22 thereof. When desired, the opening 21 may be closed by the lacing 23.

When the tube 20 is inflated, pressure on 70 the outer casing 10 is relieved by the spiral casing 19 so that while the desired cushion effect is obtained, the danger of splitting the outer casing or tearing away the connection between the casing and the hame rim at 75 17 will be eliminated.

To reinforce the collar, and at the same time take up the wear at certain places, I provide leather protectors 24.

What is claimed is:

A horse collar comprising a cushion member, a hame rim carried thereby, said cushion member and said hame rim being formed of a single length of material, a reinforcing member within said hame rim, a pneumatic 85 tube within said cushion member, said cushion member being provided with an opening to facilitate the inserting or removal of said pneumatic tube, and a length of tape wound spirally about said pneumatic tube to 90 relieve pressure from said cushion member when said tube is inflated, substantially as described.

In testimony whereof I affix my signature.

CECIL B. MAYFIELD.
